UNITED STATES PATENT OFFICE.

IRVIN E. ROCKWELL, OF CHICAGO, ILLINOIS.

DESIGN FOR AN END PIECE FOR BOOKCASE-TOPS.

SPECIFICATION forming part of Design No. 32,453, dated April 3, 1900.
Application filed October 12, 1899. Serial No. 733,438. Term of patent 14 years.

To all whom it may concern:

Be it known that I, IRVIN E. ROCKWELL, a citizen of the United States, residing at Chicago, in the county of Cook and State of Illinois, have invented and produced a new and original Design for End Pieces for Bookcase-Tops, of which the following is a specification.

My design is shown in the accompanying drawing, which is a perspective view.

The novel feature of my design consists in the peculiar figuration of the end piece, which has plane parallel side surfaces A, a plane rear surface or edge, as indicated at B, and plane end surfaces C D, parallel to each other and at right angles to the rear edge. The front edge of said end piece is composed of the compound curve E F, the curved sections joining at about midway of the height of said end piece and the curved portion F merging at its upper end into the plane surface C.

The entire end block presents, when viewed in side elevation, a rectangular figure as to the major portion of its surface, while its front edge presents a compound curve, forming at the lower end an acute angle with the lower surface of the block and merging into the plane surface of the upper end of the block at its upper end. 25

A subordinate feature of my design consists in the parallel depressions G H, which extend from the plane surface C to the curved portion E, over the surface of the curved edge F, and in the scroll I in the surface A. 30

I claim—

The design for an end piece for bookcase-tops substantially as shown and described. 35

IRVIN E. ROCKWELL.
